POWER PLANT

Application filed December 16, 1927. Serial No. 240,604.

This invention relates to improvements in power plants, and more particularly to improvements in generating units of a type in which an internal combustion engine is directly connected to a generator.

An object of this invention is to provide a direct connected power plant which is neat and compact in arrangement, which will provide for a maximum ease of assembly and repair, and which is economical to construct and maintain.

Another object of the invention is to provide, in a device of the class described, an improved, novel governing and timing mechanism, mounted on a member or bracket, common to various minor assemblies of the engine, the bracket being removable as a unit, whereby the adjustments of the governor and timing assemblies may be made on the bench, apart from the engine. By this mode of construction, it is possible to effect quickly and accurately all routine adjustments of the minor assemblies, when removed from the engine.

A further object of this invention is the provision of an improved and efficient cooling system, comprising a means for cooling the engine by vapor, and comprising a novel arrangement of cooling fans and air ducts adapted to direct and confine a current of cooling air about the upper portion of the engine and through a radiator or condenser. The cooling system further attains the object of controlling the temperature of the lubricating oil in the crank case.

Further objects and advantages of this invention will appear from the drawings and the following detailed description.

It will be understood that the hereinafter described construction embodies a specific working example of a device constructed in accordance with this invention, and that the specific construction illustrated may be modified so as to be adapted to a multi-cylinder engine as well as to one having a single cylinder.

Further, that the arrangement and construction of the various connections, ducts, passages and other interconnecting means may be varied substantially, that the exact construction and arrangement of the various minor assemblies of the engine may be varied

substantially; that the foregoing and other changes may be made in the construction illustrated without departure from the spirit, scope, and full intendment of the invention, the example shown being merely a single experimental embodiment of the invention which is submitted in compliance with the statutory requirements relating to applications for Letters Patent.

In the drawings Fig. 1 is a longitudinal section of a preferred form of our power plant; Fig. 2 is an elevation of the inside face of the governor bracket, showing the various minor assemblies adapted to be mounted thereon.

Referring by numerals to the drawings, 10 designates the crank case, which is preferably a casting serving as a frame for the assembly, and on which is mounted a cylinder casting 11. This comprises a cylinder 12 in which operates the working piston 13. The piston may be of any suitable form. The cylinder casting 11 is separate from, and carried by the crank case casting, and comprises valve guides 14, tappet guides 15. The guides serve to position and to determine the path of travel of valves 16 and tappets 17 respectively, both of which may be of any suitable conventional type. Mounted upon the member 11, and formed separately therefrom, is the cylinder head 18 provided with a passageway or opening 19 in communication with the combustion space 20. The head 18 may be provided with an opening to receive a spark plug 21, or equivalent ignition device.

A condenser or radiator 22 is located by preference above the cylinder head 18, and is disposed horizontally in order to minimize the over-all height of the plant. The condenser 22 and the cylinder head 18, as well as other adjacent parts of the plant may be surrounded and enclosed by a hinged cover 23. For convenience in lifting the cover, it is preferably made of a light material, such as sheet metal, and may be provided with a retaining device such as a spring clip, (not shown), to prevent any movement or vibration thereof during the operation of the engine. The top portion of the cover 23 consists of a screen 24. This

permits the free passage of cool air through the top of cover 23 and serves as a guard for the parts enclosed thereby. The cover 23 not only directs the air through the condenser or radiator, but causes a sufficient circulation of air over the cylinder head to permit the use, if preferred, of an air cooled head. If desired, the cover 23 may be made heavy enough to serve as a support for the condenser. It is more desirable however, to hinge the cover as shown, to give access to the top portion of the engine without disconnecting any parts.

Operating in the crank case, and projecting therethrough to the generator, is a crank shaft 25, on the inside end of which is a crank arm 26. The construction of the crank shaft and crank arm constitute this assembly as one of the so called "overhung" type. A connecting rod 27 serves as the operative connection between crank arm 26 and the piston 13. The crank is provided with a counterweight 28 which may be secured to the crank shaft by means of bolts 29, or if desired may be formed integrally therewith. By the use of a counterweight for balancing, the moment of reciprocating parts is balanced, both about the axis of the crank arm, and about the axis of the crank shaft.

30 The crank shaft 25 is supported and carried by a bearing plate 30 and a bearing 31. These serve also as bearing members for the generator, hereinafter described. The bearing plate 30 is fastened to the crank case or frame 10, which carries a member 32 within which the fly wheel 33 rotates. The fly wheel is keyed to the crank shaft, and is provided with a plurality of peripherally disposed web-like members 34 which serve the purpose of fan blades to move the air for cooling purposes. The path of the cooling air is herinafter described. Endwise movement of the fly wheel 33 is prevented by means of a plate 35 and a collar 36, in a manner which will be apparent from the drawings.

In the generator the armature is shown at 37. This may be of any suitable form and is preferably mounted on a sleeve 38, after the manner described in the application of Alfred C. Boock, filed December 16, 1927, Serial No. 240,466. The sleeve 38 is firmly positioned on shaft 25 by a collar 36 and a nut 39. The sleeve construction for mounting the armature offers the advantages of ease of removal of the armature for service or repair; the sleeve is of especial value in increasing the stiffness and rigidity of the shaft 25.

60 The bearing 40 may be carried by member 41, formed by the generator case 42, which may in turn be attached to the crank case 10. Suitable pole pieces 43 are preferably attached to the flanged portion 44 of the generator case 42.

Located at one end of and within the crank case 10 is a governor bracket 45 which serves to carry a governor shaft bearing 46. In this bearing is rotatably mounted a hollow shaft or rotatable sleeve 47 which is driven from the crank arm 26 by means of a driving arm 48. The driving arm engages a pin 49, by means of a slot, or fork 50, (see Fig. 2), the slotted construction serving to eliminate the necessity for accurately aligning the governor bracket 45 with respect to the crank shaft 25. A pair or more of governor weights 51 may be pivoted onto the arm 48 by means of pivot pins 52. The weights serve to actuate a spindle 53 which is slidably mounted inside of the hollow shaft 47. A governor spring 54 serves to oppose the movement of weights 51, when the latter are under centrifugal influence. The outer end of the spindle 53 is in contact with one arm of a bell-crank lever 55. The lever 55 is arranged to rotate partly about a fixed pivot. The other arm of the lever 55 is positioned to engage, and is opposed by a spring 56. At its upper or outer end, the spring 56 is provided with a threaded adjustment 57 which projects through the crank case wall or through the end cover plate therefor, as shown. An external adjusting nut 58 is provided on the threaded member 57. By movement of the nut 58, the pressure on spring 56 may be either increased or decreased, thereby affording means for adjusting the action of the governor while the engine is in operation. One of the arms of the lever 55, or the pivot therefor, is in connection with a throttle operating mechanism (not shown), by which the governor is enabled to control the speed of the engine. This mechanism is described in detail in the co-pending application of Adolph Rosner, filed December 16, 1927, Serial No. 240,524.

A pinion 59 is attached to the governor sleeve 47 on the opposite side of the governor bracket 45. Engaging this pinion there is a cam gear 60 which in turn is mounted on and serves to rotate a cam shaft 61. The inner end of the shaft 61 carries cams 62 and 63 for the operation of the engine valves. Gear 60 may be positioned on this shaft by means of a lock nut 64. The governor bracket 45 carries a pair or more of brackets designated as 66 and 67 serving respectively to carry pivots for rockers 68 and 69, (see Fig. 2). The rockers are provided respectively with cam contact surfaces 70 and 71, which serve as intermediate operative connections between the cams and valve tappets. The pinion 59 preferably serves to drive a timer gear 72 which may be disposed opposite the cam gear 60. The timer gear serves to operate a timer of conventional construction, the timer case being shown at 73. The timer is mounted on a shaft 74 which may also serve as a shaft to drive the oil pump, hereinafter described in connection with the lubricating system. A

spring member 75, or its equivalent, is employed to position the timer case.

It will be seen from the above description and the drawings that the cam gear and cams, 5 governor assembly, the timer assembly and the oil pump, with their driving mechanisms, are all carried by the governor bracket 45, disposed in an end opening of the crank case. As a closure plate for this opening, there is 10 provided a member 120, preferably so arranged that studs 121 may serve to position both the bracket and closure plate. The timer 73 preferably derives its immediate support from the plate member 120. By the 15 removal of bracket 45, either together with, or following removal of plate 120, all of the described minor assemblies may be moved from the engine and plant, so that any adjustments, repairs, replacements, or timing 20 adjustments may be made on the bench while the various minor assemblies are easily accessible.

It will be seen from the drawings and description that the generator serves to complete 25 the enclosure of one end of the crank case. The opposite end of the crank case, outside of the governor bracket 45, and the plate member 120, is enclosed by a cover 76.

Air for cooling the motor and also the air 30 for mixture with the fuel in the carburetor is drawn through openings 77 in the end cover 76, and this flow of air is regulated by means of a pivoted shutter 78 provided with openings 79, which are so disposed as to be brought 35 into register with the openings 77. Beneath the crank case proper, and below the oil chamber is an air duct 80, preferably disposed longitudinally of the engine and serving to connect the openings in end cover 76 40 with the fan blades 34 on the fly wheel. The generator end of the crank case 10 is preferably separated from the crank chamber 81 by means of plates 82 and 83 which form a housing 45 for the fly wheel and also form the cooling air passages at this point. Besides drawing air through the air duct 80, as described, some of the air for cooling and combustion may be introduced through the generator by means of the openings 84 in the 50 generator case 42. All of the air drawn in through either of the two routes described is discharged upwardly through a passage 85, which is an air passage up through crank case 10. At 86 is indicated the fuel tank 55 which is preferably cast integral with the main casting comprising the crank case 10, etc. This fuel tank is preferably of horse-shoe shape so as partially to surround the cylinder casting 11, including the cylinder 12. 60 As the air passes upwardly through the passage 85 it is carried past the adjacent wall of the fuel tank, and thus assists in keeping the fuel at a safe and uniform temperature. 65 As the cooling air proceeds upwardly past the fuel tank its course is determined by the

hinged cover 23, by which the air stream is compelled to pass upwardly and outwardly through the radiator or condenser 22.

In connection with the air circulating system, the present invention embodies means 70 for cooling the lubricating oil and cooling the fuel supply in the tank 86. As described, the air in passing through the air duct 80, under the crank case, is brought into immediate cooling contact 75 with the bottom of the crank chamber 81, in which is located the oil supply. This stream of air is thus utilized for cooling the oil in the crank chamber. The air duct 80 may be provided with ribs (not shown) ex- 80 tending longitudinally of the duct or passage. In addition, the bottom of the crank chamber 81 may be provided with internal, upwardly extending ribs (not shown), ex- 85 tending up into the body of lubricant in this chamber. In practice it is found that the passage of air beneath the crank chamber keeps the oil supply reasonably cool at all times. This cooled oil, in splashing up 90 against the walls of the fuel tank 86, aids materially in maintaining at a low temperature the contents of the fuel tank. Excessive cooling of the lubricating oil is prevented by control of the pivoted shutter 78, described 95 above. The described apparatus contemplates the use of a combined splash and pressure lubricating system, but it will be seen that the cooling system for the oil is obviously adaptable to either system of lubrication alone. 100

In the above connection the shape and location of fuel tank 86 is of advantage in presenting a substantial surface to the cooling air stream. In other engines having a cast 105 in fuel tank, it has customarily been located either in the base or the sub-base and away from the engine proper. In order to keep the temperature of the fuel at all times safely below the flash point the tank may be insulated from the cylinder 12 by an air space 90, 110 which may be divided by a heat insulating shield 91. The fuel tank is also heat insulated from the water jacket hereinafter described, by means of a narrow gasket 92, 115 thereby providing a horizontal air space 93. The vertical wall of the fuel tank 86 is by 120 preference used to form part of the air passage from the fly wheel 33 to the radiator 22. If preferred, upwardly extending ribs (not 125 shown), may be added to the outer wall of the fuel tank to increase further the cooling effect from this air stream. Additional cooling of the fuel tank may be obtained by providing openings, (not shown), in the webbed portion of the fly wheel 33, thereby causing air to circulate under that portion of the fuel tank which overhangs the fly wheel, as shown at 94. The cooling effect may still be 130 further increased by cooling ribs or fins (not

shown), placed on the bottom wall of the fuel tank.

The cooling system for the head and cylinder proper of the engine, is of the vapor type, comprising essentially a short cooling jacket 95, below which is located the air space 90, above described. The level of the liquid in the jacket is determined by the height of a filler opening 96, and this level is such that the jacket is not completely filled. During operation of the engine, vapor rises through tubes 97 up into the vapor condenser or radiator 22, where it is condensed and returned by gravity, either through the vapor riser tubes 97 or through an additional tube 98. The end of the radiator or condenser 22 opposite the vapor lead 97, may be provided with a small opening (not shown), leading to the atmosphere, in order to prevent the system from becoming air-bound. There is no tendency for vapor to escape through this opening because the capacity of the condenser is sufficient to condense all of the vapor before it reaches the opening. For this reason the system will very seldom require additional water or cooling fluid. It will be seen from the drawings that the location of the condenser above the cylinder head and cooling jacket eliminates the necessity of a pump for returning condensed liquid to the system. The system offers the further advantage of enabling the use of cooling media of various boiling points, thus permitting an exact temperature control of the engine.

While we have shown and described the cylinder head as being jacketed, and vapor cooled, it will be understood that due to the volume of air delivered by the fly wheel fan, an air cooled head may just as well be used.

The oiling system in the described plant construction is of the combined splash and pressure type. All of the rotating and moving parts inside of the crank case, as well as the piston and the wrist pin bearing, are splash lubricated. In addition thereto, certain of the bearing surfaces are pressure lubricated by an oil pump designated as 99. The oil pump is of the gear type, carried by the governor bracket 45 and driven through the timer shaft 74 by the timer gear 72, as described above. The inlet 100 of the oil pump communicates with the oil storage space in the bottom of crank chamber 81, the outlet of the pump being shown at 101. The pump proper consists of a pair of gears 102 and 103, one of which is carried by the timer shaft as described, and the other of which may be mounted on a stub shaft 104 as shown. Lubricating oil enters the pump by means of the inlet 100, passes between the gears 102 and 103, thence through oil passages 105, 106, 107, and 108, to the connecting rod bearing 109. If desired, an oil passage may be formed in or carried by the connecting rod,

and the oil forced therethrough to the piston pin bearing. In the example illustrated, the piston pin is satisfactorily oiled by splash. Auxiliary piping may serve to force the oil to the governor shaft and the cam shaft, and to other locations desired to be force oiled (see Fig. 2). The passage 106 is preferably formed by the hollow member 110 slidably mounted in the pump case 111, and is forcibly held in contact with the packing 112 and member 113 by means of the spring 114. The hollow member 110 is prevented from excessive horizontal movement by means of the stud bolt 115 extending up into the opening 116 in the hollow member 110.

The above described spring-held connection at the outlet of the oil pump enables the removal of the entire oil pumping mechanism from the engine, and further eliminates the necessity of providing a hand hole for connecting the oil pump after it is in place. Thus it is seen that the oil pump which is carried by governor bracket 45 is removable from the engine along with the cam operating mechanism and the governor assembly as above described.

The described construction of the engine and plant embodies a novel carburetor and fuel control means forming the subject of the above mentioned co-pending application of Adolph Rosner.

The plant as described has been designed and adapted for use either with or without storage batteries. When intended for use with storage batteries a novel reverse-current cutout has been provided in connection with a governor control switch, the governor and cutout being adapted through a mechanical linkage for adjustable governor control, by the governor described in the present application. The reverse-current cutout and switch assembly may be associated with a suitable panel, and the mechanism and connections may be enclosed to form an assembly such as that indicated at 117. Manual control of the switch for starting, is effected by a lever 118, which may be of any suitable form. The novelty of construction of the reverse-current cutout and the governor control switch, form the subject matter of a co-pending application of Adolph Rosner, filed December 16, 1927, Serial No. 240,524.

We claim:

1. In an internal combustion engine having a pressure lubricating system, a crank case having a wall opening and a removable closure plate therefor, a lubricant pump within the crank case, a mounting member for the pump, mounted within the crank case, adapted to permit the pump to be connected to and removed from the engine, and means adapted upon such connection and removal to make and sever a lubricant connection from said pump to the engine.
2. In an internal combustion engine, a

crank case, a crank shaft, a cam shaft assembly, a governor assembly, and a removable bracket within the crank case and distinct from its wall portions, adapted to carry said assemblies, and adapted to permit adjustment and timing of the valve operating mechanism, apart from the engine.

3. In an internal combustion engine, a crank case, a crank shaft, a cam shaft assembly and an oil pump, a removable bracket within the crank case and distinct from the wall thereof, for supporting the cam shaft and pump, said assembly and pump being adapted to be driven from the crank shaft, said cam shaft and pump being adapted by the removal of said supporting bracket for complete adjustment of valve action and the oil pump external to said engine, and means forming a socketed driving connection for said assembly and pump, adapted for engagement with the crank shaft upon application of said bracket to the engine, and means forming a socketed telescoping connection for said pump, when the bracket is mounted on the engine.

4. In an internal combustion engine, a crank shaft, a governor assembly and an oil pump, a removable supporting bracket common to the governor assembly and pump, and being adapted, upon the removal of said supporting bracket, to permit complete adjustment of said governor and pump external to the engine and means associated with the governor and pump for effecting driving and fluid connections upon application of the bracket to the engine.

5. In an internal combustion engine having electric ignition, a crank shaft, a crank case, a timer and a lubricant pump, a removable supporting structure common to the timer and the pump, adapted to permit timing of said engine and adjustment of the lubricant pump, apart from the engine, and means forming an automatic lubricant pump connection within the crank case, upon application of said supporting structure to the engine.

6. In an internal combustion engine, a crank case having a removable end plate, an ignition timer carried thereby, a cam shaft assembly, an oil pump assembly and governor assembly, a removable bracket common to said assemblies, and disposed within the crank case, gearing for said assemblies, disposed between the end plate and bracket, the end plate and bracket being removable, as a unit, to permit complete adjustment of the several said assemblies and timer, apart from the engine.

7. In an internal combustion engine, a crank case, having a removable end plate, a cam shaft assembly, a governor assembly and a lubricant pump, a removable mounting member for said assemblies and pump, said member disposed within the crank case and positioned by the end plate, and adapted to

permit removal of said valve operating mechanism, governor assembly and pump, as a unit, from the engine.

8. In an internal combustion engine having electric ignition, a crank case having a removable end member, a cam shaft assembly, and an oil pump assembly, a removable mounting bracket common to said assemblies, an ignition timer carried by said end member, said end member and bracket arranged to permit adjustment of valve and ignition timing, the governor assembly, and oil pump, apart from the engine.

9. In an internal combustion engine, a crank case, a crank shaft, a governor assembly, a valve-timing assembly and an oil pump, a removable mounting member within the crank case and common to said assemblies and pump; said assemblies and pump being operatively inter-connected and adapted to be driven by the crank shaft, and said mounting member constituting means whereby full adjustment of speed control, valve timing and pump may be effected when said elements are removed from the engine.

10. In an internal combustion engine, a crank case, a crank shaft, a cam shaft, a governor, an oil pump for said engine, a bracket removably mounted within the crank case and carrying said cam shaft, governor, and oil pump, said cam shaft, governor and pump being operatively interconnected and adapted to be driven by the crank shaft, said removable bracket constituting means whereby full adjustment of valve timing, and the speed control of said engine may be effected, apart from the engine.

11. In an internal combustion engine, an oil pump and an oil conduit, companion means on the pump and conduit adapted to effect a telescoping connection therebetween upon assembling the pump to the engine, and without manual access to the connection.

12. In an internal combustion engine, an oil pump, a removable bracket carrying the pump, an oil conduit, a crank case forming an enclosure for the pump and conduit, and an extensible telescoping connection therebetween, adapted to permit connecting the oil pump to the conduit upon positioning the bracket, and without access to the interior of the enclosure.

CHARLES B. JAHNKE.
ALFRED C. BOOCK.
